UNITED STATES PATENT OFFICE.

HINSDALE SMITH AND ARTHUR P. SMITH, OF SPRINGFIELD, MASSACHUSETTS.

METAL VEHICLE-BODY.

No. 878,205.

Specification of Letters Patent.

Patented Feb. 18, 1908.

Application filed May 8, 1907. Serial No. 372,631.

To all whom it may concern:

Be it known that we, HINSDALE and ARTHUR P. SMITH, citizens of the United States of America, residing at Springfield, in the county of Hampden and State of Massachusetts, have invented new and useful Improvements in Metal Vehicle-Bodies, of which the following is a specification.

This invention relates to an improvement 10 in metal vehicle bodies of the type shown and described in our prior United States Letters Patent No. 813,460 dated February 27, 1906.

The particular object and purpose of this 15 invention is to provide means for strengthening the door construction and especially the fastening means between the door-sill, side-plates of the body, and rear seat, so that any possibility of the rear seat plate becoming loosened or weakened from the side plate of the body is prevented.

This improvement, broadly, is designed to provide a construction that will securely fasten the rear seat to the body portion of 25 the vehicle and overcome certain objections to the ordinary structures now in use.

Referring to the drawings forming part of this application,—Figure 1 is a perspective view of a portion of the metal vehicle body 30 showing our improvement. Fig. 2 is a sectional view on the line 2—2 of Fig. 1 looking in the direction of the arrow and showing the metal at the forward edge of the rear seat folded inward and the riveting for securing 35 the sill facing to the said turned-in portion of the rear seat. Fig. 3 is a sectional view on the line 3—3 of Fig. 1 looking in the direction of the arrow and showing the relation between the sill, sill-facing, and the outward 40 turned edge of the body-plate with the securing means therefor. Fig. 4 is a perspective view of a portion of the door-way showing a modification of our improvement.

Referring to the drawings in detail, *a* designates the usual sheet metal side-plate of the body portion of the vehicle to which is secured the inside rail or sill *b* by means of the screws *c*, or other suitable fastening devices, that pass through the side-plate *a* and into 45 the usual reinforcing strip *d* for the sill-plate.

The floor of the vehicle body is designated by *e*, and the forward seat of a touring car-

body at *e*. The rear side-plate is designated at *e*.

The side-plate *a* is extended below the sill 55 *f* and is secured to the same by means of the screws *g*.

The edge portion of the sheet metal side-plate that is cut away to form the opening for entrance to the rear seat is bent inward 60 at right angles to the outer face portion *a*, and overlies the inside rail or sill *b*, as clearly shown in Fig. 3 at *h*.

i designates the sill facing-plate. Generally, in practice, the plate *e* and the plate *a* are made in separate pieces and usually have relative movement between the same. To overcome this serious defect, the sill facing-plate, instead of stopping short at the junction or dividing line between the side-plate 70 *a* of the body and the sheet metal plate *e* of the rear seat, as shown at 44 in Fig. 1 of our prior Patent, extends flush with the top rail *v* or edge portion of the rear seat. This side-plate *e* of the rear seat at the door-way 75 is turned inward, as designated at *k* in Fig. 2, and riveted to the sill-facing *i*, as shown at *m*, but below this, the lower and forward portion of the sill-plate *i* is secured by screws *j* to the wood reinforcing strip *d*, as clearly 80 shown in Fig. 3. It will therefore be seen that the vehicle body is very much strengthened by making the sill facing-plate *i* of one continuous piece and riveting the same to the bent-in portion *k* of the sheet metal 85 forming the rear side-plate *e*.

We have found, by experience, that this structure effectively prevents any possibility of the rear side-plate *e* becoming loosened from its fastening with the side-plates of the 90 body, and prevents any relative movement between the same.

It will be noticed that the continuous sill facing-plate *i* extends from the rear side of the forward seat to the top forward upper 95 edge of the rear seat and that the reinforcing strip *d* also extends from the junction of the plates *a* and *e* to the rear side of the forward seat and nearly to the upper edge of the same.

Referring to the modification in Fig. 4, in 100 which the forward portion of the door-way, (instead of being curved as shown in Fig. 1) is made angular and preferably a right angle between the horizontal and vertical portions

of the door-way, the reinforcing strip *d* would preferably be made in two pieces, and likewise the facing plate *i*, as shown in said Fig. 4. Otherwise the construction is in all 5 respects the same.

What we claim is:—

1. In an improvement of the class described in combination with the side-plates of a vehicle body and the door-sill, a sill 10 facing plate extending from the forward seat to the forward upper edge of the rear seat.

2. As an improvement in vehicle bodies of the class referred to, in combination with the 15 side plates of the body and rear seat, said plates being bent in the same direction and at right angles to the outer side of said plates, a facing plate secured to the bent portions

of said plates, said facing plate extending from the lower rear side of the forward seat 20 to the forward edge of the rear seat, as described.

3. A metal body of the class described consisting of a body portion and rear seat portion thereon, the edge of the side plate of the rear seat portion being turned inward at the edge of the door, and a stiffening plate secured to said in-turned edge and extending downwardly from the upper forward edge of the rear seat to the sill and secured to the 25 body.

HINSDALE SMITH.
ARTHUR P. SMITH.
